C. GERTZBEIN

BUMPER

Filed Sept. 21, 1923

Fig. 3.

Inventor:
Carl Gertzbein
J.W. J. Dennis, atty.

UNITED STATES PATENT OFFICE.

CARL GERTZBEIN, OF TORONTO, ONTARIO, CANADA.

BUMPER.

Application filed September 21, 1923. Serial No. 664,110.

To all whom it may concern:

Be it known that I, CARL GERTZBEIN, a subject of the King of Great Britain, and resident of the city of Toronto, county of 5 York, Province of Ontario, in the Dominion of Canada, have invented certain new and useful Improvements in Bumpers, as described in the following specification and illustrated in the accompanying drawings,

10 that form part of the same.

The principal objects of this invention are to devise a structure which will be extremely resilient and will be capable of absorbing extraordinary shocks, affording extraordinary 15 protection to the car to which it is fitted.

A further object is to devise a strong and durable structure which may be produced at low cost.

20 The principal feature of the invention consists in supporting the bumper bar on vertically disposed toggles and arranging strong springs to hold the toggles extended and to receive and absorb the shocks of 25 impact.

In the drawings, Figure 1 is a side elevational view of one of the bumper bar supporting units.

Figure 2 is a plan view of the unit shown 30 in Fig. 1.

Figure 3 is a sectional detail of one of the supporting brackets showing the manner of securing and supporting the toggle.

In the construction of bumper herein 35 illustrated rigid bracket members 1 adapted to be secured to the frame of the car, are each formed with a vertical slot 2 arranged behind a cup-shaped portion 3. The forward side of the slot is sloped upwardly and downwardly in a forward direction 40 from the horizontal axis of the cup which presents a horizontal V-shaped bearing.

A pair of flat bars 4 and 5 are pivotally mounted on a bolt 6 extending transversely 45 through the slotted portion of the bracket, said bolt cutting the axial line of the cup so that the edges of the bars rest upon the sloped surfaces 7 and 8 respectively of the slot. The bars project forwardly from the 50 bracket and are of equal length.

Similar bars 9 and 10 are pivotally connected to the forward ends of the bars 4 and

5 and the ends of these bars are pivotally secured together by a bolt 11.

A cup member 12 of corresponding shape 55 to the cup portion 3 of the bracket 1, and formed with a similar vertical slot, embraces the forward ends of the bars 9 and 10 and is secured by the bolt 11 which passes transversely therethrough on the axial line of the 60 cup.

A toggle member is thus formed which will contract and expand freely.

A coiled compression spring 13 is arranged between the cup members and normally holds the toggle extended. 65

The outer cup members 12 are formed at the outer end to support the bumper bars 14 here shown as tubes and these bumper bars may be of any suitable design. 70

In the use of the device, the toggle members are secured to the forward ends of the car frame and the springs hold the whole structure rigid and free from rattle. In the event of the bumper bars engaging an obstruction the springs will be compressed and the toggle bars pivoting on their pivotal connections will fold easily without resistance and immediately the pressure is removed the springs resume their normal 75 shape and the toggles extend.

A device so constructed is extremely flexible and will not bind in operation and will present an increasing resistance to any impact as the springs compress. It also presents a pleasing appearance on the front of a car. 85

What I claim as my invention is:—

1. A bumper, comprising, vertically operable toggle members, a bar joining said toggles, and spring means for holding the toggles extended. 90

2. A bumper comprising, vertically operable toggle members, a bar joining said toggles, and compression springs arranged 95 within the said toggles adapted to hold them extended.

3. A bumper comprising, rigid bracket members each having vertical slots, a pair of bars pivoted in the slot of each bracket, bars pivoted together and pivotally connected to the ends of the aforesaid bars, means for carrying a bumper bar secured to the outer connected ends of the outer bars, 100

and compression springs arranged horizontally between said pairs of bars.

4. A bumper comprising, rigid bracket members each having cupped ends and vertical slots formed with forwardly sloping surfaces, bolts extending horizontally through said slots, toggle bars pivoted on

said bolts, cup members secured to the outer ends of the toggles, spiral compression springs having their ends housed in said cups and holding the toggles extended, and bumper bars supported by the outer cup members.

10

CARL GERTZBEIN.
